(57) **CLAIM**

The ornamental design of an electrode with conductive pattern, as shown and described.

DESCRIPTION

FIG. 1 is a front and bottom perspective view of an electrode illustrating an electrode with conductive pattern, configured in accordance with the present invention;

FIG. 2 is a left side view of the electrode;

FIG. 3 is a right side view of the electrode;

FIG. 4 is a front view of the electrode;

FIG. 5 is of a back view of the electrode;

FIG. 6 is a bottom view of the electrode illustrating the electrode conductive pattern; and,

FIG. 7 is a top view of the electrode.

The broken lines in the drawings depict portions of the electrode with conductive pattern that form no part of the claimed design.

1 Claim, 3 Drawing Sheets
